US0D1069397S

(12) **United States Design Patent** (10) Patent No.: **US D1,069,397 S**
(45) Date of Patent: ** Apr. 8, 2025

(54) **BABY CARRIER**

(71) Applicant: **Hongwei Wang**, Changzhou (CN)
(72) Inventor: **Hongwei Wang**, Changzhou (CN)
(**) Term: **15 Years**
(21) Appl. No.: **29/893,478**
(22) Filed: **May 31, 2023**
(51) LOC (15) Cl. **03-05**
(52) U.S. Cl.
USPC **D3/214**
(58) **Field of Classification Search**
USPC D3/213, 214, 215
CPC A47D 13/02; A47D 13/025
See application file for complete search history.

(57) **CLAIM**

The ornamental design for a baby carrier, as shown and described.

DESCRIPTION

FIG. 1 is a first perspective view of a baby carrier showing my new design;

FIG. 2 is a second perspective view thereof;

FIG. 3 is a front view thereof;

FIG. 4 is a back view thereof;

FIG. 5 is a left side view thereof; and,

FIG. 6 is a right side view thereof.

1 Claim, 6 Drawing Sheets
